UNITED STATES PATENT OFFICE.

SVEND MARTIN MEYER, OF BROOKLYN, NEW YORK.

DEVICE FOR LIGHTING LAMPS BY ELECTRICITY.

SPECIFICATION forming part of Letters Patent No. 705,773, dated July 29, 1902.

Application filed January 3, 1898. Serial No. 665,434. (No model.)

To all whom it may concern:

Be it known that I, SVEND MARTIN MEYER, a citizen of the United States, and a resident of Brooklyn, New York, have invented a new and useful Improvement in Devices for Lighting Lamps by Electricity, of which the following is a specification.

In the accompanying drawings, Figure 1 is an elevation, partly in section, of an oil-lamp and attachments embodying my invention. Fig. 1^a is a bottom view of the same. Figs. 2, 3, and 4 are detail views, hereinafter more particularly referred to. Figs. 5 and 6 are vertical sections of portions of the burner. Figs. 7 and 11 are detail horizontal sections of the same. Fig. 8 is a bottom view of the burner. Figs. 9 and 10 are detail vertical sections. Fig. 12 is a detail elevation showing a modification hereinafter described. Fig. 13 is a plan of the same.

Referring to Fig. 1, 1 represents the body of the lamp; 2, the base; 3, the burner; 4, the wick, and 5 the chimney. 8 represents the fixed sparking point, formed of an angular vertical projection and "grounded" on the shell of the lamp. 9 is a vertical rock-shaft carrying the vibrating sparking point 10, mounted in suitable bearings 11 and moved in either direction by the lever or handle 12. In order to insure the completion of the stroke of the lever in either direction, the said lever works in contact with a doubly-inclined track 13, formed of spring-wire, the shape of which produces pressure upon the lever as it approaches its mid-stroke and causes it to be thrown to the end of its stroke in either direction by the resilience of the spring. The batteries 19 and 20 are removably mounted in the base 2 of the lamp by means of a clip 28 and the bearing 30, formed at its ends with pins or sockets, one of which engages with a stud or a socket 31, while the other is caught by a pin or aperture, as the case may be, near the end of an elastic arm 33, secured within the base of the lamp. The battery 19 is connected at 21 with the shell of the lamp and connected by wire 22 with the battery 20 and this by the wire 23 with the induction-coil 24, connected by an insulated wire 18 with a hinged arm 17, engaging in a clip 16, which is connected to an insulated spring-arm 15, bearing upon the vertical

rock-shaft 9, as shown in the sectional view Fig. 5.

Fig. 2 shows a top view of the hinged arm 17 and its clip by which the connection is made when the burner is placed in position on the lamp-reservoir.

Fig. 3 shows on a larger scale in elevation the said hinged arm 17 and in dotted lines 60 a flexible wire 17^a, which may be substituted for the hinged arm, as illustrated in Fig. 4, where 17^b represents a terminal socket in the said flexible wire fitting over a pin 16^a, mounted in the lamp-burner, in lieu of the clip 16 65 and in like manner connected by the insulated spring-arm 15 with the vibrating sparking point 10.

In the modification shown in Figs. 6 to 9 the conductor 18 is fixed in the frame or lamp-body 1 and when the burner 3 is placed in position connects with an insulated ring 14 in the burner, as shown in Fig. 9, electrically connected, through the spring 14^a, with the vertical rock-shaft or vibrating rod 9, 75 which carries the vibrating sparking point 10 and is vibrated by the hand-lever 12. Where either of the forms of connection illustrated in Figs. 2, 3, 4, and 5 are used, the rock-shaft 9 is insulated from the burner by 80 being stepped in an insulated socket-piece 11, as shown in Fig. 5. In this instance the vertical rock-shaft 9 is electrically connected with the clip or socket 16 through the spring 15.

In the modification shown in Figs. 10 and 85 11, the vertical rock-shaft is provided with a flat or squared portion 9^a, against which latter the spring 15^b rests, so as to serve also to carry the rock-shaft to its full stroke.

In the modification shown in Fig. 12 inclined 90 plates 13^a are provided as a substitute for the spring 13 to insure the complete stroke of the vibrating sparking point 10. The plates 13^a are insulated by plates 13^b, of mica or other material, to prevent electrical con- 95 ductions when the vibrating sparking point 10 comes in contact with them. In vibrating the sparking point 10 in either direction it rides over one of the plates 13^a, which deflects it upward as it approaches the fixed sparking point 8 and engages with the protuberant end thereof, from which it escapes with a sudden movement and is received by the other inclined insulated plate 13^a, so as to carry it to 100

the end of its stroke and prevent its contact with the metal of the lamp.

An important practical advantage results from having one of the contact-points in fixed position, as I am thereby enabled to accurately locate the spark in proximity to the lamp-wick. Furthermore, where both members have any considerable degree of flexibility or mobility they must overlap to such an extent 10 in engaging that the excessive length of the actuated member endangers tearing the wick.

Having described my invention, the following is what I claim as new therein and desire to secure by Letters Patent:

15 1. The combination of a lamp-body containing a suitable source of electricity, a burner removably mounted thereon, a conductor separably connecting the source of electricity in the body with a fixed conductor 20 in the removable burner, connected with lighting device adjacent to the lamp-wick, a vibrating contact-making device on the burner closing the circuit at mid-stroke only and automatically thrown to either extremity 25 of its movement when moved by hand from the opposite extremity, to close the circuit as described.

2. In a device for lighting oil-lamps by electricity, the combination of a lamp-body 1, a 30 burner 3 removably mounted thereon, a suitable source of electricity in the body of the lamp, a fixed sparking point 8 adjacent to the lamp-wick, a vertical rock-shaft 9, a contact-spring 11 carried by said rock-shaft and engaging with the sparking point 8, a horizontal 35 arm 12 for rotating the rock-shaft 9, a spring device throwing the rock-shaft to the extremity of its movement when moved to mid-stroke from either direction, and separable conductors 40 tors from the respective poles of the source

of electricity to the connections of the sparking points 8 and 10, permitting the removal of the burner from the body of the lamp in which the source of electricity is mounted, substantially as described. 45

3. In a device for lighting oil-lamps by electricity, the combination of a lamp-body containing a suitable source of electricity; a lamp-burner removably mounted thereon, the contact-piece 8, inclined insulating bearing-surfaces 13^a adjacent thereto, a vibrating contact-spring 10 sliding upon the bearing-surfaces 13^a and engaging with the fixed point 8, and separable conductors connecting the respective poles of the source of electricity 55 with the contact-points 8 and 10, substantially as described. 50

4. In a device for lighting oil-lamps by electricity, the combination of a lamp-body 1, containing a suitable source of electricity, a 60 burner 3 removably mounted thereon, a fixed contact-point 8 adjacent to the wick, a vibrating contact-spring 10 engaging with the contact-point 8 at mid-stroke, inclined insulated bearing-surfaces 13^b on either side of the contact-point 8 arranged to deflect the vibrating contact-spring 10 as it is moved toward the contact-point 8 from either direction and throw it to the opposite extremity of its stroke, means for imparting vibratory movement to the spring 10 and separable conductors connecting the respective poles of the source of electricity with the contact devices 8 and 10, and permitting removal of the burner from the body of the lamp, substantially as de- 65 scribed. 70

SVEND MARTIN MEYER.
